Primary Examiner — Anhdao Doan(74) *Attorney, Agent, or Firm* — David J. Chang(57) **CLAIM**

The ornamental design for an instrument for medical and laboratory diagnosis, as shown and described.

DESCRIPTION

FIG. 1 shows a front elevational view of an instrument for medical or laboratory diagnosis;

FIG. 2 shows a front left side perspective view thereof;

FIG. 3 shows a left side elevational view thereof;

FIG. 4 shows a rear elevational view thereof;

FIG. 5 shows a rear right side perspective view thereof;

FIG. 6 shows a right side elevational view thereof;

FIG. 7 shows a top plan view thereof; and,

FIG. 8 shows a bottom plan view thereof.

The broken lines illustrate unclaimed portions of the instrument for medical and laboratory diagnosis and form no part of the claimed design.
